UNITED STATES PATENT OFFICE

HELEN WELDER, OF SAN ANTONIO, TEXAS

DESIGN FOR A NAPKIN CLIP OR SIMILAR ARTICLE

Application filed November 7, 1930. Serial No. 37,583. Term of patent 3½ years.

To all whom it may concern:

Be it known that HELEN WELDER, a citizen of the United States, residing at San Antonio, in the county of Bexar and State of Texas, have invented a new, original, and ornamental Design for Napkin Clip or Similar Article, of which the following is a specification, reference being had to the accompanying drawings, forming part thereof.

I claim:—

The ornamental design for a napkin clip or similar article, as shown.

HELEN WELDER.
